US00D977352S

(12) **United States Design Patent** (10) Patent No.: **US D977,352 S**
Greenwood et al. (45) Date of Patent: ** Feb. 7, 2023

(54) **NOTIFICATION APPLIANCE**

(71) Applicant: **Carrier Corporation**, Farmington, CT (US)

(72) Inventors: **Thomas Greenwood**, Farmington, CT (US); **Martin Paul Robotham**, Farmington, CT (US)

(73) Assignee: **CARRIER CORPORATION**, Palm Beach Gardens, FL (US)

(**) Term: **15 Years**

(21) Appl. No.: **29/815,553**

(22) Filed: **Nov. 15, 2021**

Related U.S. Application Data

(62) Division of application No. 29/723,075, filed on Feb. 4, 2020, now Pat. No. Des. 939,990, which is a division of application No. 29/627,843, filed on Nov. 30, 2017, now Pat. No. Des. 880,324.

(57) **CLAIM**

The ornamental design for a notification appliance, as shown and described.

DESCRIPTION

FIG. 1 is a perspective view of a notification appliance; FIG. 2 is a front view of the notification appliance of FIG. 1;

FIG. 3 is a right side view of the notification appliance of FIG. 1;

FIG. 4 is a left side view of the notification appliance of FIG. 1;

FIG. 5 is a first end view of the notification appliance of FIG. 1;

FIG. 6 is a second end view of the notification appliance of FIG. 1; and,

FIG. 7 is a back view of the notification appliance of FIG. 1.

The broken lines illustrate portions of the notification appliance that form no part of the claimed design.

1 Claim, 6 Drawing Sheets
